OFFSET NIPPLE

William E. Kelly, Jersey City, N.J., assignor to The Thomas & Betts Co., Elizabeth, N.J., a corporation of New Jersey

Filed Aug. 31, 1961, Ser. No. 66,571

Term of patent 14 years

(Cl. D91—3)

FIG. 1 is a perspective view of an offset nipple showing my new design;

FIG. 2 is an end elevation thereof;

FIG. 3 is a side elevation thereof;

FIG. 4 is an elevation thereof as seen from the opposite end of FIG. 2; and

FIG. 5 is a fragmentary side elevation thereof as seen from the opposite side of FIG. 3.

The side of the article not shown is substantially the same in appearance as the side shown.

I claim:

The ornamental design for an offset nipple, as shown and described.
